UNITED STATES PATENT OFFICE.

GEORGE W. DOOLITTLE, OF MONTROSE, PENNSYLVANIA, ASSIGNOR OF
ONE-HALF OF HIS RIGHT TO W. C. CRUSER, OF SAME PLACE.

WAGON-POLE.

SPECIFICATION forming part of Letters Patent No. 224,403, dated February 10, 1880.

Application filed September 27, 1879.

To all whom it may concern:

Be it known that I, GEORGE W. DOOLITTLE, of Montrose, in the county of Susquehanna and State of Pennsylvania, have invented certain new and useful Improvements 5 in Wagon-Poles; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a plan of my wagon-pole, and Fig. 2 is a 15 detail view of the same.

The nature of this invention relates to poles for carriages and other vehicles in which a pole or tongue is employed.

My improvement consists in the construction and arrangement of rigid and adjustable 20 braces with a pole, whereby the same may be readily applied to vehicles varying in width, as fully set forth in the following specification, and particularly pointed out in the claim.

Referring by letter to the drawings, A designates the pole; B B, angular-shaped braces bolted to the rear end thereof, and C C brace- 25 rods which are bolted to the outer ends of the braces B and to the sides of the pole A.

D D designate sliding braces, which are 30 formed with the eyes E, for the purpose of connecting the same with the axle-clips, and these braces are bent near their eyes so as to bring the latter in position for such purpose.

Each brace D is provided at its end which is 35 nearest to the pole with a clevis, F, which em-

braces the brace B, and is arranged to slide thereon.

G G designate square-shaped collars which fit loosely around the united ends of the braces 40 B and C and the sliding braces D.

As shown in Fig. 2, the brace-rods C are formed with lugs or flanges d at their ends for the purpose of maintaining the collars in place when the set-screws e are tightened up. The 45 collars or clevises F are also provided with set-screws f.

In order to adjust the eyes so as to fit the pole to a carriage or sleigh the set-screws are partly unscrewed, and the sliding braces D 50 slipped out or in, according to the distance between the axle-clips. The set-screws are then tightened up, whereby the braces D D will be held rigidly in place.

What I claim, and desire to secure by Letters Patent, is—

The sliding braces D, with eyes E, and collars or clevises F, arranged to pass around and slide upon the braces B, in combination with the pole A, the braces B, the braces C, formed 60 with lugs d and bolted at their ends to braces B, the loose collars G, arranged to fit over the braces, and the tightening-screws, as shown and set forth.

In testimony that I claim the above I have 65 hereunto subscribed my name in the presence of two witnesses.

G. W. DOOLITTLE.
